UNITED STATES PATENT OFFICE.

CARL HANS VOM BAUR, OF DOUGLASTON, NEW YORK.

ELECTRIC FURNACE.

1,385,411.

Specification of Letters Patent. Patented July 26, 1921.

Application filed December 30, 1918. Serial No. 268,910.

To all whom it may concern:

Be it known that I, CARL HANS Vom BAUR, a citizen of the United States, and a resident of Douglaston, in the county of 5 Queens and State of New York, have invented certain new and useful Improvements in Electric Furnaces, of which the following is a specification.

My present invention relates to electric furnaces, and particularly those embodying three electrodes, and has for its object to insure a uniform or approximately uniform distribution of the current, or rather of the heat produced thereby, particularly in cases 15 where a three phase distribution of current is employed. In order to obtain this result, I have devised a novel shape of the furnace, and a novel arrangement of the electrodes within such furnace, as will now be explained in detail, and particularly pointed out in the appended claims.

Reference is to be had to the accompanying drawings, in which:

Figure 1 is a vertical section on the plane 25 indicated by the line 1—1 of Fig. 2, representing a satisfactory and preferred embodiment of my invention;

Fig. 2 is a horizontal section, substantially on the line 2—2 of Fig. 1;

Fig. 3 is a partial vertical section on line 30 3—3 of Fig. 2; and

Fig. 4 is a diagram illustrating certain relations in the contour shape of the furnace, as set forth hereinafter.

At T, I have indicated a transformer by which a polyphase current supplied through the wires 10, 11, 10' (say from an ordinary alternator, not shown) is converted into suitable three-phase current, to be led through 40 the three wires 12, 13 14 to the electrodes 15, 16, and 17 respectively of the electric furnace. Of course, if a three-phase current of suitable (generally low) voltage is available directly, the transformer T will not be 45 required. The electrodes pass through the top or roof 18 of the electric furnace, made of any suitable refractory material. The said electrodes are preferably employed in a vertical position, as shown, and are also 50 preferably adjustable up and down, for which purpose they may pass or slide through suitable holders, indicated at 19.

The furnace, which in plan view is of a generally elliptical shape at least at the slag 55 line (plane of section 2—2), is provided with a discharge spout 20, primarily for the pouring of the metal or other material

under treatment, which preferably forms part of the electric circuit. This spout may be located at any suitable point, say at one 60 of the ends of the furnace. The furnace bottom or body 21 is preferably cup-shaped and is provided with one or more doors 22, one directly behind the spout 20, and the other, say diametrically opposite. By opening these doors, access is had to the interior of the furnace for the purpose of inspection, patching, charging, rabbelling off slag, etc.

With the three-phase, three-wire arrangement described, each of the three electrodes will receive the same amount of current, and they will therefore develop like amounts of heat. The aim of my invention is to insure that, under these conditions, 75 every point of the side wall of the body 21 at the contour of the slag line, will receive approximately the same total or aggregate amount of heat from the three electrodes, when the mass within the furnace is molten. 80 To meet this requirement accurately, the outline or contour, at the slag line should be formed, theoretically, according to a curve of constantly changing radius of curvature similar to an ellipse; for practical purposes, 85 however, it will be sufficient to have this contour composed of two circular arcs at the middle of the furnace, having their common center at the point or lower end of the central electrode 16, and two circular 90 arcs at the ends of the furnace, the centers of these end arcs being in line with and equidistant from, the center of the middle arcs. The centers of the end arcs are at the 95 points or lower ends of the lateral electrodes 15, 17 when the latter are in their normal working position. The operative ends of the three electrodes are therefore normally in line with each other (either exactly or approximately) along what may be 100 termed the major axis of the furnace, with the two lateral electrodes at equal distances from the central electrode. The radius of the middle arcs is greater than that of the end arcs, and there is a definite novel relation, to be explained presently, between the major and the minor axes of the contour and the distance separating the lateral electrodes from the central electrode. In the 105 preferred example illustrated by Figs. 1, 2 and 3, the lateral electrodes 15, 17 are just half-way between the central electrode and the ends of the major axis, and in this particular case, taking the distance from the

110

central electrode to one of the lateral electrodes as the unit, 1, the radius of the middle arcs would have to be approximately 1.28 (the radius of each end arc in this case being 1). In the construction shown adjacent arcs are connected by straight lines tangent thereto.

- To develop and explain the general relations between the several dimensions of the 10 furnace, or rather of its contour, reference will be made to the diagram Fig. 4, where C designates the location of the central electrode, D and E the location of the lateral electrodes, F the generally elliptical contour 15 of the furnace (at the slag line), viewed in plan, A a point of said contour in line with D C E, and B a point of said contour on a line (minor axis) drawn through the center C perpendicular to the major axis A D C E. 20 Let a designate the major radius (A C), b the minor radius (B C), e the eccentricity (C D or C E) of the points D and E, and d the distance from the point B to either of the points D and E. 25 Inasmuch as each electrode produces an equal amount of heat, and inasmuch as the heat at any point is in inverse ratio to

the square of its distance from the source of heat, the heat at the point A will be

30

$$\frac{1}{(a-e)^2} + \frac{1}{a^2} + \frac{1}{(a+e)^2}$$

and the heat at the point B will be

35

$$\frac{1}{b^2} + \frac{1}{d^2} + \frac{1}{d^2}$$

or

$$\frac{1}{b^2} + \frac{2}{d^2}$$

40

$$\frac{1}{b^2} + \frac{2}{b^2 + e^2}$$

Since it is desired to have an equal amount of heat at the points A and B, we have the 45 equation

$$(1) \quad \frac{1}{(a-e)^2} + \frac{1}{a^2} + \frac{1}{(a+e)^2} = \frac{1}{b^2} + \frac{2}{b^2 + e^2}$$

Now let m designate the ratio between a and e , that is to say, let $a=me$, and further let x designate the ratio between b and e (in other words, let $b=xe$) and substituting this in equation (1) we obtain

$$(2) \quad \frac{1}{(me-e)^2} + \frac{1}{m^2e^2} + \frac{1}{(me+e)^2} = \frac{1}{x^2e^2} + \frac{2}{x^2e^2 + e^2},$$

or

$$(2a) \quad \frac{1}{e^2(m-1)^2} + \frac{1}{m^2e^2} + \frac{1}{e^2(m+1)^2} = \frac{1}{x^2e^2} + \frac{2}{e^2(x^2+1)}$$

multiplying by e^2 , we obtain

$$(3) \quad \frac{1}{(m-1)^2} + \frac{1}{m^2} + \frac{1}{(m+1)^2} = \frac{1}{x^2} + \frac{2}{x^2+1}$$

and further

$$(4) \quad \frac{m^2(m+1)^2 + (m-1)^2(m+1)^2 + m^2(m-1)^2}{(m-1)^2m^2(m+1)^2} = \frac{3x^2+1}{x^4+x^2},$$

or

$$(4a) \quad \frac{3m^4+1}{(m^3-m)^2} = \frac{3x^2+1}{x^4+x^2}$$

and

$$(5) \quad x^4+x^2 = \frac{(3x^2+1)(m^3-m)^2}{3m^4+1}$$

or

$$(5a) \quad x^4+x^2 - \frac{3x^2(m^3-m)^2}{3m^4+1} - \frac{(m^3-m)^2}{3m^4+1} = 0$$

$$(6) \quad x^4 - x^2 \left(\frac{3(m^3-m)^2}{3m^4+1} - 1 \right) - \frac{(m^3-m)^2}{3m^4+1} = 0$$

$$(7) \quad x = \sqrt{\frac{1}{2} \left(\frac{3(m^3-m)^2}{3m^4+1} - 1 \right) + \sqrt{\left[\frac{1}{2} \left(\frac{3(m^3-m)^2}{3m^4+1} - 1 \right) \right]^2 + \frac{(m^3-m)^2}{3m^4+1}}}$$

- 55 For the purpose of simplifying the calculation of numerical examples, we may designate the fraction

$$\frac{(m^3-m)^2}{3m^4+1}$$

60

by a single term, say p , thereby reducing

equation (7) to the more convenient form

$$(8) \quad x = \sqrt{\frac{3p-1}{2} + \sqrt{\left(\frac{3p-1}{2} \right)^2 + p}} \quad 65$$

In the specific construction illustrated by Figs. 1 2 and 3, the distance between the

two lateral electrodes is equal to the diameter of the circles of which the end arcs form parts, or in other words, $a=2e$, and therefore $m=2$. In this preferred form of my 5 invention, we have

$$p = \frac{36}{49} = .7347$$

and

$$10 \quad x = \sqrt{.6021} + \sqrt{.6021^2 + .7347} = 1.2815.$$

Of course, when $e=1$, as assumed in connection with Fig. 2, and $m=2$, x becomes equal to b , and the minor radius or half-diameter of the elliptical contour has thus 15 been indicated in Fig. 2 as equal to 1.2815. For practical purposes, the value 1.28 is a sufficiently close approximation. The minor axis of the elliptical figure is in this particular case equal to .64 times the major 20 axis. However, the values of a and e may be selected arbitrarily as most convenient in each particular case, and the corresponding value of b determined therefrom with 25 the aid of the equation or formula given above under (7) or (8).

In the operation of my improved furnace, I prefer to extend the vertically-adjustable electrodes to the mass of material under 30 treatment, and to have the conducting molten bath of metal or other material form part of the circuit between the electrodes.

With the new arrangement described, I am enabled, when operating with a three-phase current and three conductors or wires 35 leading to the electrodes, to obtain a practically uniform heating of the side wall of the furnace throughout its contour, and I thus avoid temperature strains which might 40 cause deformation or other injury to said furnace wall. In furnaces of this general type employing, at the electrodes, a current of more than two phases, a uniform heating of the side wall throughout its contour has 45 not been obtained hitherto, and this resulted in objectionable features. It will be obvious that the relatively hot portions of an unevenly heated side wall will burn out more quickly than others, and on the other hand, 50 the relatively cooler portions are likely to cause trouble on account of an uneven melting action. If the furnace is used, say for melting a cold charge of metal, this material will melt less at the relatively cooler 55 portions of the side wall, and in order to mitigate this defect and to hasten the melting, it has been the practice heretofore to open the furnace doors and to push the unmelted metal from such cold spots into the 60 hotter portions of the furnace. All of this is unnecessary when my improved arrangement is adopted, which insures a distribution of the electric current and a heating effect 65 (temperature gradient) which are practically uniform throughout the marginal por-

tion of the furnace. Much greater durability and efficiency are thus secured by my improved furnace, the oval or elliptical form of which is also of advantage in giving the molten bath a relatively large surface area. 70 This is of special value when treating metals, since the thoroughness of the refining action depends largely on the quantity of slag in contact with the metal to be treated, and this quantity is increased, relatively, when 75 using an oval form of furnace as described.

In the particular form illustrated, my invention is applied to an electric furnace of the arc type, the three electrodes of which are connected to wires supplied with three-phase currents, and specifically to the conductors of the low-tension side of a transformer or alternator. However, I do not limit myself to the so-called "delta" connection shown in Fig. 1, but may use equivalent means, such as the "star" or Y connection. These modifications and others may be made without departing from the nature of my invention as defined in the appended claims. 80

It will be understood that in a furnace constructed in accordance with the principle of the present invention uniform temperature of the furnace walls and consequently uniform action of the slag on the walls will be maintained. The corrosion of the walls, therefore, will be substantially uniform at different points along the walls. This is due to the fact that the aggregate heating effect of the electrodes, with uniform energy in 90 each arc, is practically the same at different points along the walls, for example, at the ends of the major and minor axes. The statement that the heat is practically the same as used here and in the claims is intended to define the condition in the furnace which has been constructed substantially in accordance with the principle of the invention, as defined in the specification. 95

Even without extraneous means for the 100 automatic regulation of the electric heat, a furnace of the construction set forth, will insure a practically uniform application and distribution of heat, the thermal efficiency of the furnace being also increased since 105 the heat gradient is practically the same in all parts of the furnace. 115

I claim:

1. An electric furnace whose contour in plan view, is of generally elliptical shape with three electrodes adapted to be supplied with three-phase current and placed one at the center of said furnace, and the others at equal distances therefrom on the major axis of said furnace at such points as to 120 satisfy the equation

$$\frac{1}{(a-e)^2} + \frac{1}{a^2} + \frac{1}{(a+e)^2} = \frac{1}{b^2} + \frac{2}{b^2 + e^2},$$

where a indicates one-half of the major 130

axis on which the electrodes are situated, b one-half of the minor axis, and e the distance from the central electrode to each of the lateral electrodes.

- 5 2. An electric furnace whose outline, in plan view, comprises two end portions curved according to arcs of circles of equal radii but different centers, and two middle portions curved according to arcs of a circle 10 whose center is in line with, and equidistant from, the centers of the end arcs; the radius b of the middle arcs, the distance e between the center of the middle arcs and the centers of the end arcs, and the distance a from the 15 center of the middle arcs to those points of the end arcs which are in line with the centers of all the arcs, being so proportioned as to satisfy the equation

$$20 \quad \frac{1}{(a-e)^2} + \frac{1}{a^2} + \frac{1}{(a+e)^2} = \frac{1}{b^2} + \frac{2}{b^2 + b^2 + e^2}.$$

3. An electric furnace whose contour, in plan view, comprises two end portions curved according to arcs of circles of equal 25 radii but different centers, the distance between said centers being equal to the diameter of said circles, and two middle portions curved according to arcs of a circle the center of which is halfway between the 30 other two centers, and the radius of which is about 1.28 times the radius of one of the end arcs.

4. An electric furnace whose contour, in plan view, is of generally elliptical shape, 35 with three electrodes adapted to be supplied

with three-phase currents and placed one at the center of the furnace and the others on the major axis of said figure, halfway between the center and the ends of such axis, the minor axis being equal to about .64 times 40 the major axis.

5. An electric furnace whose contour, in plan view, is of generally elliptical shape, with three electrodes located within the furnace, and a three-phase, three-wire circuit 45 connected with said electrodes, the latter being so placed that at the slag line at the periphery the aggregate heating effect of the three electrodes with uniform energy in each arc is practically the same at the ends 50 of both the major and the minor axis of the furnace.

6. An electric furnace whose contour, in plan view, is substantially elliptical, with a plurality of electrodes so located within said 55 contour that at the slag line at the periphery the aggregate heating effect of all the electrodes with uniform energy in each arc is practically the same at the ends of the major axis of said figure as at the ends of its minor 60 axis.

7. An electric furnace whose contour, in plan view, is a curvilinear figure, with a plurality of electrodes so located within said 65 contour that at the slag line at the periphery the aggregate heating effect of all the electrodes with uniform energy in each arc is practically the same for all points of said curvilinear contour figure.

CARL HANS VOM BAUR.
